UNITED STATES PATENT OFFICE

ELWIN H. KIDDER, OF CHICAGO, ILLINOIS, ASSIGNOR TO LINK-BELT COMPANY, OF CHICAGO, ILLINOIS, A CORPORATION OF ILLINOIS

ROTARY CAR DUMPER

Application filed December 9, 1927. Serial No. 238,819.

My invention relates to improvements in rotary car dumpers and has for one object to provide a new and improved form of car dumper wherein by the use of a counter-weight and lever the car may be clamped in position on the cradle and wherein the force exerted by the clamping means is adjustable to support the heaviest load that can be brought upon the mechanism without at the same time exerting a pressure sufficient to damage the lightest and flimsiest type of car. Another object is to provide a clamp holding mechanism. Another object is to provide a clamping mechanism where the counter-weights supporting the load are located entirely off the cradle. Other objects will appear from time to time in the course of the specification and claims.

My invention is illustrated more or less diagrammatically in the accompanying drawings, wherein—

Figure 1 is a transverse section;

Figure 2 is a section along the line 2—2 of Figure 1;

Figure 3 is a section in the same plane as Figure 1 showing the car in the dumping position;

Figure 4 is a detail view;

Figure 5 is a section along the line 5—5 of Figure 4;

Figure 6 is a section along the line 6—6 of Figure 4;

Figure 7 is a section along the line 7—7 of Figure 2.

Like parts are indicated by like characters throughout the specification and drawings.

A is a foundation structure preferably of concrete and the like containing a receiving hopper A¹ with room inside the foundation beneath the receiving hopper for material handling apparatus which since it forms no part of my present invention is not here shown or illustrated. A² is a framework supported within the foundation and overlying the hopper. Mounted on this framework and upon the hopper are supporting blocks A³ A³ upon which are pivoted equalizing beams A⁴ A⁵, with rollers A⁶, one on each end of the equalizing beams. A⁷ A⁷ are roller rings one supported on the rollers A⁶

A⁶ at each end of the structure. A²⁰ is a structural steel cradle mounted on and supported by the roller rings A⁷. This cradle is generally U-shaped in cross section, being built up by structural shapes as indicated 55 and the cradle with the roller ring is supported and free to rotate on the rollers A⁶. A⁸ is a transfer table extending longitudinally of the cradle from end to end. This transfer table carries car tracks A⁹ adapted 60 when the cradle is in the upright position to be in line with the fixed car tracks A¹⁰ on the foundation. This transfer table is supported on rollers A¹¹ adapted to travel on transverse tracks A¹² on the cradle so that 65 the transfer table may move to one side to permit the car A¹³ on the tracks on the transfer table to move laterally toward the left from the position shown in Figure 1 as the cradle rotates to bring the side of the car into 70 engagement with the cushion A¹⁴. The engagement of the car with the cushion is shown in Figure 3.

Spaced along one side of the U-shaped cradle are a series of vertical guideways or 75 stanchions B. Traveling along each of these guideways or stanchions is a clamp carriage B¹, the clamp carriage being provided with track engaging elements B² whereby the carriage is free to travel along the guideway 80 but held against rotation with respect thereto. This clamp carriage has a lug B³ overhanging the top of the car A¹³, the arrangement being such that when the clamp is in the down position this lug engages the top 85 of the car A¹³ as shown in Figure 3. Pivoted on this lug is a clamp beam B⁴ having a car engaging face B⁵ which when the car is in the dumping position, engages the top of 90 the car as shown in Figure 3. It will be noted that the car engaging face B⁵ is relatively short whereas the car engaging lug B³ is quite long, the reason for this being that the cars are of different widths and since the side of the car always engages the cushion 95 no matter what the size of the car is, the face B⁵ will come into engagement with its top but if the car is narrow it is necessary for the lug B³ to be widely extended to engage the car no matter where it comes. B⁶ is a 100

stop interposed between the clamp B^4 and the lug B^3 whereby the angular rotation of the clamp arm with respect to the lug is limited. It will be noted that in the inoperative position, the surface B^5 extends down below the car engaging surface of the lug B^3 so that this surface comes into engagement with the car first and as the carriage continues to descend the clamp beam rotates with respect to the carriage until both the surfaces B^5 and B^2 are in engagement with the car.

Referring now to the means for raising or holding the clamp in the raised position above the car, attention is drawn first to Figure 7. C is a curved track on one of the track rollers. In this track travels a carriage C^1 . This carriage has an arm C^2 adapted to engage a stop C^3 on the equalizing beam A^5 . A cable C^4 is dead ended on the carriage C^1 which carriage it will be noted is free to travel along the track C . This cable extends around a sheave C^5 on the roller ring back around a sheave C^6 thence up around a sheave C^7 . It will be noted that there is one of these lifting carriages on each of the roller rings and the cable C^4 between the sheave C^6 and the two sheaves C^7 is divided and one branch of the cable goes over each of the sheaves C^7 but over a guide sheave C^8 , thence over a sheave C^9 at the top of the stanchions B and thence down where each of these cable parts is dead ended on a link C^{10} , which link is concentric with the pivot axis of the clamp arm B^4 on the carriage B^1 . When the parts are in the position shown in Figure 7, the lifting carriage is drawn away from the sheave C^5 by its engagement with the stop C^3 and raises the clamps out of engagement with the car. If the roller ring rotates in a counterlockwise direction in Figure 7, the tension on the hoisting rope caused by the weight of the clamp and carriage will cause the carriage C^1 to remain in engagement with its stop, thus shortening the distance between the carriage C^1 and the sheave C^5 as the roller ring rotates. This continues until as the cradle rotates the clamps have settled down against the car at which time there will be no further tension on the cable C^4 and the carriage C^1 will remain at rest in its track and travel away from the stop.

D is a brake shaft, there being one for each clamp. On this brake shaft is a brake wheel D^2 associated with a brake band D^2 . D^3 is a brake lever fulcrumed adjacent to one end of the band D^2 at a point adjacent the fulcrum. D^4 is a powerful spring tending normally to operate the lever and lock the brake drum D^1 against rotation. D^5 is a cam track projecting upwardly from the foundation adjacent to the brake drum D^1 . D^6 is a bell crank lever pivoted on the arm D^7 on the cradle having a roller D^8 adapted to engage the cam track D^5 . A link D^9 extends from the

other arm of the bell crank lever to the free arm of the bell crank lever D^{10} , the other arm of which carries a roller D^{11} adapted to engage the brake lever D^3 so that when the parts are in the upright inoperative position shown in Figure 4, the cam track D^5 through the two bell crank levers and links compress the spring D^4 to release the tension on the brake band D^2 and permit the brake shaft D to rotate. This condition continues as long as the roller D^8 is in engagement with the cam. As the cradle rotates in a counter clockwise direction referring to Figure 4, toward the dumping position, the time comes when the roller D^8 goes out of contact with the cam D^5 . At this time the brake spring is no longer compressed but is allowed to exert a tension on the brake band, lock the brake band and brake shaft against rotation, the parts remaining so locked until upon return movement the cradle comes back to the upright position.

Mounted on and held against rotation with respect to the brake shaft D are a series of compound differential pulleys E . E^1 , there being one associated with each stanchion B . Dead ended on the pulley E is a drum rotating or take-up cable E^2 , which cable travels over a sheave E^3 at the lower end of the pillar B thence up over a sheave E^4 and around a sheave E^5 at the upper end of the pillar and thence down where it is dead ended on the link C^{10} to which is dead ended the hoisting cable. E^6 is a spring take-up interposed in the cable and forming a part of it, there being thus a separate spring take-up for each of the clamps. E^7 is a clamp holding cable. It is dead ended on the larger radius of the compound pulley E^1 and adapted to be wound about it in a direction opposite to the winding of the take-up cable E^2 . This cable E^7 extends across beneath the cradle around the sheave E^8 thence up over a sheave E^9 at the outboard end of the clamping arm, thence over a sheave E^{10} on the clamp carriage, the axis of rotation of this carriage being the same as the axis of rotation of the clamp and also the same as the axis upon which the link C^{10} is pivoted. The cable E^7 extends down thence over a sheave E^{11} and then up to the bell crank lever E^{12} upon which it is dead ended.

The lever E^{12} is pivoted on the lug F . It engages a stop F^1 which holds it against rotation in a counter clockwise direction as shown in Figure 1; extending from the free end of this lever is a cable F^2 traveling up over a sheave F^3 on a counterweight tower F^4 , thence down around a sheave F^5 on the counterweight F^6 thence up around a sheave F^7 down around a fixed curved guide member F^8 across beneath the cradle around a curved guide member F^9 and then it extends to the arm F^{10} on the cradle where it is dead ended. The arrangement of this is such that

the weight of the counterweight F^6 tends to rotate the lever in a clockwise direction bringing it into engagement with the stop F^1 and when in this position it serves as an abutment against which the cable E^7 may pull, the cable E^7 being anchored on the other end on the differential pulley. When, however, with the parts starting in the position shown in Figure 1 the cradle is rotated toward and into the position shown in Figure 3, as long as the spring brake is held out of engagement, the differential drum is free to rotate and as the cradle rotates and as the clamps descend they draw out on the hoisting cable and create a slack in the holding cable but since the take-up cable is drawn out as the hoisting cable is slackened up the take-up cable tends to rotate the differential pulley and wind in on the holding cable. During this time the free end of the holding lever is moved toward the top on the counterweight tower and the same is true of the part of the cradle on which the other end of the counterweight cable F^2 is dead ended so that the counterweight tends to descend. The equalizing spring in the take-up cable compensates for difference in the contour of the car and since the two sides of the holding cable are shortened more rapidly than the one section of the take-up cable is taken up. There will be a winding up of the holding cable on this part of the differential pulley at a more rapid rate than the unwinding of the take-up cable from its part of the differential pulley. The result of this is that after about thirty degrees travel the clamp will have settled down against the car, the cable will be tight and the brake will be put on. Then as the cradle rotates further and as the clamp lever travels away from the counterweight tower the angle through which the cable pulls on the clamp lever will increase, the leverage will increase and the tension of this counterweight cable will tend to rotate the clamp lever away out of contact with its abutment thereby increasing the tension on the holding cable as is shown in Figure 3.

It will be understood that under ordinary conditions the car begins to dump its contents long before it reaches the upside down position as shown in Figure 3 and the mechanism under ordinary conditions never has to support the entire weight of the car and its load. If, however, the load should be frozen into the car it might happen that the clamps might have to carry a load made up of the weight of the car and its frozen contents. Under these conditions it sometimes will happen that the weight of the car will overcome the counterweight but if it does, it will only overcome it to bring the clamp lever back against its abutment. Thus under these conditions the counterweight is out of operation and it becomes possible to provide a relatively

light counterweight, one sufficient to hold the ordinary loads encountered and at the same time light enough not to crush a light or flimsy car. One purpose of the counterweight then is to take up additional slack in the cable holding the clamps, and to exert an additional tension on the car to take care of the occasional situation where a lump of coal or something of that kind is caught between the car and the clamp. When and if the weight of the counterweight is overcome the load is then carried by the cable held between the abutment against which the lever engages and the brake.

On the return movement of course the operation is just the opposite.

The cradle is rotated by means of a drive shaft G carried in pillow blocks G^1 driven by a motor not here shown. Each end of the drive shaft carries a pulley G^2 about which is wound a rotating cable G^3 , the cable being dead ended at either end on spring abutments G^4 on the roller rings, the cable being wound about the ring as indicated in Figure 1. Rotation of the motor in one direction or the other causes the cradle to rotate in a clockwise or counter clockwise direction as the case may be.

The differential pulley is differential merely in order to compensate for the fact that as the clamp comes down the cable E^7 on both sides of the car is shortened and the cable E^2 extending from the clamp downwardly is lengthened and means must be provided so that the cable remains always right. This is accomplished in the preferred form by means of the differential pulley.

Manifestly this spring take-up might be located in the cable or in the link C^{10} or might take the form of a spring support for the sheaves E^3 or E^4 . It will be noted that this take-up is not located in the load carrying part of the system but merely in that part of the system between the differential pulley and the clamp carriage B^1 . It has nothing to do then with the position of the clamp and is not affected in any important way by the presence or absence above the car of any foreign matter, lumps of coal or the like which might and frequently do prevent seating of the clamp surfaces B^1 and B^5 against the car. Any change in operation resulting from presence of or subsequent collapse of such material is taken care of by the cable F^2 which transmits the power of the counterweight F^6 to the lever E^{12} and rotates the lever away from its abutment F^1 to set up an initial tension in the clamp holding cable system.

The spring take-up E^6 does not function until after point B^5 of clamp is seated on the car or on some obstruction. Up to this time the differential drum acts to wind in cable E^7 as fast as it is paid out by lowering of the clamp. The amount paid out is twice the

4

movement of the clamp due to the two-part reeving of the rope E^7 about the clamp. The cable E^2 however has a single part reeving to the carriage and therefore moves only as far as the clamp or half as far as the cable E^7 .
 5 To compensate for this the two diameter differential drum is used. When the clamp seats itself on the car the point B^5 strikes first and stops. Carriage B^1 moves on down to the top of the car rotating the clamp beam about the pivot of sheave E^{10} . During this movement the cable E^7 is paid out only an amount equal to the movement of carriage B^1 , instead of acting as a two part line, and paying out twice that amount, as it does during
 10 the part of the clamp movement up to the time when B^5 strikes the car. The differential drum, of course, is so proportioned as to wind an amount of holding rope equal to
 15 double the movement of clamp carriage B^1 and pay out an amount of rope E^2 equal to the movement of the carriage. Since, however, during the last part of the movement carriage B^1 only is moving, and point B^5 is
 20 stationary the two to one ratio of rope movements is changed to a one to one ratio, some means of compensating is necessary or the carriage B^1 would be held back by rope E^2 prevented from coming to its seat on the car.
 25 At this time spring E^6 comes into play by elongating a sufficient amount to make up for the two to one ratio of movements which is created by the different diameters of the differential drum. Spring E^6 is to have only
 30 sufficient carrying capacity to insure rotation of drum E^1 to wind in cable E^7 , but should deflect easily under the weight of carriage B^1 after point B^5 has seated and the weight of clamp has been relieved from lifting ropes C^4 .
 35 40 I claim:
 1. In a car dumper comprising a rotary car supporting cradle, a car clamp movable thereon toward and from the car, a clamp holding cable in engagement with the clamp at all positions thereof, a lever upon which one end of the cable is dead ended, means operative only after the clamp is seated on the car for rotating the lever to exert a tension on the clamp holding cable and hold the clamp in working position to support the car.

3. In a car dumper comprising a rotary car supporting cradle, a car clamp movable thereon toward and from the car, a clamp holding cable in engagement with the clamp at all positions thereof, a lever upon which one end of the cable is dead ended, means operative only after the clamp is seated on the car for rotating the lever to exert a tension on the clamp holding cable and hold the clamp in working position to support the car, said means comprising a counterweight and a tractor upon which the counterweight is mounted independent of the cradle, and a cable interposed between the counterweight and the lever.

4. In a car dumper comprising a rotary car supporting cradle, a car clamp movable thereon toward and from the car, a clamp holding cable in engagement with the clamp at all positions thereof, a lever upon which one end of the cable is dead ended, means operative only after the clamp is seated on the car for rotating the lever to exert a tension on the clamp holding cable and hold the clamp in working position to support the car, said means comprising a counterweight and a tractor upon which the counterweight is mounted independent of the cradle and a cable interposed between the counterweight and the lever, the cable being dead ended on the lever extending over a sheave on the counterweight guide, thence over a sheave on the counterweight, thence back over a second sheave on the counterweight guide to and dead ended on the cradle.

5. In a car dumper comprising a rotary car supporting cradle, a car clamp movable thereon toward and from the car, a clamp holding cable in engagement with the clamp at all positions thereof, means operative only after the clamp has seated on the car for exerting a tension on the cable to hold the car and clamp in position, and a separate structure upon which said means are in part supported independent of the cradle.

6. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle.

7. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, the

tension exerting means being removed from the cradle.

8. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, the tension exerting means comprising a lever upon which one end of the cable is dead ended.

9. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, said tension exerting means comprising a lever upon which one end of the cable is dead ended, means operative only after the clamp is seated on the car for rotating the lever to exert a tension on the clamp holding cable and hold the clamp in working position to support the car.

10. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, said tension exerting means comprising a lever upon which one end of the cable is dead ended, means operative only after the clamp is seated on the car for rotating the lever to exert a tension on the clamp holding cable and hold the clamp in working position to support the car, said means being removed from the cradle.

11. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, said tension exerting means comprising a lever upon which one end of the cable is dead ended, means operative only after the clamp is seated on the car for rotating the lever to exert a tension on the clamp holding cable and

hold the clamp in working position to support the car, said means comprising a counterweight removed from the cradle and a cable interposed between the counterweight and the lever.

12. In a car dumper comprising a rotary car supporting cradle, a car clamp movable thereon toward and from the car, a clamp holding cable in engagement with the clamp at all positions thereof, means operative only after the clamp has seated on the car for positively holding one end of the cable against movement and for exerting a tension on the other end of the cable to hold the clamp and car in fixed position with respect to the cradle, said tension exerting means comprising a lever upon which one end of the cable is dead ended, means operative only after the clamp is seated on the car for rotating the lever to exert a tension on the clamp holding cable and hold the clamp in working position to support the car, said means comprising a counterweight removed from the cradle and a cable interposed between the counterweight and the lever, the cable being dead ended on the lever extending over a sheave on the counterweight guide, thence over a sheave on the counterweight, thence back over a second sheave on the counterweight guide to and dead ended on the cradle.

13. In a car dumper comprising a rotary car supporting cradle a car clamp movable thereon toward and from the car, a clamp holding cable, means for taking up the slack therein as the clamp moves toward the car and means operative only after the clamp has seated on the car for positively holding the take-up end of the cable against displacement with respect to the cradle.

14. In a car dumper comprising a rotary car supporting cradle a car clamp movable thereon toward and from the car, a clamp holding cable, means for taking up the slack therein as the clamp moves toward the car and means operative only after the clamp has seated on the car for holding the take-up end of the cable against displacement, the take-up means including a differential pulley about which the cable travels and a separate cable connection between the differential pulley and the clamp.

15. In a car dumper comprising a rotary car supporting cradle a car clamp movable thereon toward and from the car, a clamp holding cable, means for taking up the slack therein as the clamp moves toward the car and means operative only after the clamp has seated on the car for holding the take-up end of the cable against displacement, the take-up means including a differential pulley about which the cable travels and a separate cable connection between the differential pulley and the clamp, a sheave over which such separate cable connection travels being lo-

cated on the side of the clamp removed from the differential pulley.

16. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means operative only after the clamp is seated for positively holding one end of the cable against movement with respect to the cradle.

17. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated, and means operative only after the cable is so held associated with the opposed end of the cable for exerting a tension thereon to lock the car in place on the cradle.

18. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means operative only after the clamp is seated for positively holding one end of the cable against movement with respect to the cradle, the cable holding means comprising a brake operative responsive to the rotation of the cradle.

19. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated and means operative only after the cable is so held associated with the opposed end of the cable for exerting a tension thereon to lock the car in place on the cradle, the tension exerting means comprising a movable member upon which the cable is anchored and means responsive to the rotation of the cradle for displacing it.

20. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated, and means operative only after the cable is so held associated with the opposed end of

the cable for exerting a tension thereon to lock the car in place on the cradle, the tension exerting means comprising a movable member upon which the cable is anchored and means removed from the cradle and responsive to the rotation thereof for displacing it.

21. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated, and means operative only after the cable is so held associated with the opposed end of the cable for exerting a tension thereon to lock the car in place on the cradle, the tension exerting means comprising a movable member upon which the cable is anchored and means removed from the cradle and responsive to the rotation thereof for displacing it, said means comprising a counterweight.

22. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated and means operative only after the cable is so held associated with the opposed end of the cable for exerting a tension thereon to lock the car in place on the cradle, the tension exerting means comprising a movable member upon which the cable is anchored and means responsive to the rotation of the cradle for displacing it, the movable member comprising a lever on one end of which the cable is dead ended, the movable member displacement means being associated with the opposed end of the lever.

23. A car dumper comprising a rotary car supporting cradle, a car clamp movable thereon toward and from the car, a clamp holding cable, means responsive to the movement of the clamp toward its seat on the car for maintaining the cable taut independent of the position of the clamp, means for positively holding one end of the cable against movement operative only after the clamp is seated, and means operative only after the cable is so held associated with the opposed end of the cable for exerting a tension thereon to lock the car in place on the cradle, the tension exerting means comprising a movable member upon which the cable is anchored and means removed from the cradle and responsive to the rotation thereof for displacing it, a movable member comprising a lever on one end of which the cable is dead ended, a mov-

able member displacement means being associated with the opposed end of the lever.

24. A car dumper comprising a rotary car supporting cradle, a car clamp movable thereon toward and from the car, means operative responsive to the rotation of the cradle for raising the clamp away from the car, the clamp being free to descend owing to its own weight under the influence of gravity into engagement with the car as the clamp raising means are gradually released responsive to the movement of the cradle toward the dumping position, a clamp holding system comprising a cable interposed between the clamp and the cradle and movable with the clamp, means operative after the clamp has seated on the car for holding one end of the cable positively against further movement, and means associated with the other end of the cable for exerting an increased tension thereon to lock the car in position on the cradle.

25. In a car dumper comprising a rotary car supporting cradle, a car clamp movable on the cradle toward and from the car, a carriage movable on the cradle, a cable connection between the carriage and the clamp, a stop removed from the cradle extending into the path of the carriage whereby as the cradle and car approach the upright position the stop and carriage engage one another to draw out the cable and raise the clamp away from the car, a clamp holding system comprising a lever pivoted on the cradle, a positive stop against which the lever rests, a cable dead ended on the lever tending to pull the lever against the stop, sheaves on cradle and clamp over which the cable travels, a differential pulley associated with the cable, the cable anchored at one end on the clamp, extending thence to and about the differential pulley, thence about the sheaves on the cradle, thence about the sheaves on the clamp, thence about the sheave on the cradle and thence to the lever whereby the cable system is always taut independent of the position of the clamp.

26. In a car dumper, a rotary car supporting cradle, a clamp movable therein toward and from the car, a cable encircling the clamp, means for holding one end of the cable against movement while the clamp is out of contact with the car and means for taking up slack in the other end of the cable as the clamp approaches the car, means for locking the take up when the clamp is seated on the car and means associated with the first mentioned end of the cable for exerting an increased tension thereon after the clamp is seated on the car.

27. In a car dumper, a rotary car supporting cradle, a clamp movable therein toward and from the car, a cable encircling the clamp, means for holding one end of the cable against movement while the clamp is out of contact with the car and means for

taking up slack in the other end of the cable as the clamp approaches the car, means for locking the take up when the clamp is seated on the car and means associated with the first mentioned end of the cable for exerting an increased tension thereon after the clamp is seated on the car, a tension exerting means comprising a lever pivoted on the cradle upon which the end of the cable is dead ended and a counterweight associated with the lever.

28. In a car dumper, a rotary car supporting cradle, a clamp movable therein toward and from the car, a cable encircling the clamp, means for holding one end of the cable against movement while the clamp is out of contact with the car and means for taking up slack in the other end of the cable as the clamp approaches the car, means for locking the take up when the clamp is seated on the car and means associated with the first mentioned end of the cable for exerting an increased tension thereon after the clamp is seated on the car, exerting means comprising a lever pivoted on the cradle upon which the end of the cable is dead ended and a counterweight associated with the lever, a structure separate from the cradle upon which the counterweight is mounted.

29. In a car dumper, a rotary car supporting cradle, a clamp movable therein toward and from the car, a cable encircling the clamp, means for holding one end of the cable against movement while the clamp is out of contact with the car and means for taking up slack in the other end of the cable as the clamp approaches the car, means for locking the take up when the clamp is seated on the car and means associated with the first mentioned end of the cable for exerting an increased tension thereon after the clamp is seated on the car, the take up means comprising a drum about which the cable is wound and a brake for locking the drum.

30. In a car dumper, a rotary car supporting cradle, a clamp movable therein toward and from the car, a cable encircling the clamp, means for holding one end of the cable against movement while the clamp is out of contact with the car and means for taking up slack in the other end of the cable as the clamp approaches the car, means for locking the take up when the clamp is seated on the car and means associated with the first mentioned end of the cable for exerting an increased tension thereon after the clamp is seated on the car, the take up means comprising a drum about which the cable is wound and a brake for locking the drum, means for rotating the drum comprising a take up cable arranged generally in parallel with the first mentioned cable and associated with the clamp.

31. In a car dumper a car holding clamp

movable toward the car, a holding cable associated therewith, means associated with one end of the cable for taking up the slack therein as the clamp moves toward the car, means for locking the cable against retrograde movement when the clamp is seated on the car, and means associated with the other end of the cable for increasing the tension therein to draw the clamp toward the car.

32. In a car dumper a car holding clamp movable toward the car, a holding cable associated therewith, means associated with one end of the cable for taking up the slack therein as the clamp moves toward the car, and means associated with the other end of the cable for increasing the tension therein to draw the clamp toward the car, the slack take-up means comprising a take-up cable associated with the clamp, in opposition to the holding cable whereby the movement of the clamp toward the car, which causes slack in the holding cable, draws out the take-up cable, a drum about which both cables are wound in opposite directions, and means for locking the drum against rotation to prevent retrograde movement of the holding cable.

33. In a car dumper a car holding clamp movable toward the car, a holding cable associated therewith, means associated with one end of the cable for taking up the slack therein as the clamp moves toward the car, means for locking the cable against retrograde movement when the clamp is seated on the car, and means associated with the other end of the cable for increasing the tension therein to draw the clamp toward the car, comprising a lever upon which the holding cable is anchored and positive means for preventing the movement of such anchorage in a direction tending to decrease pull on the cable and means for rotating the lever to move the anchorage in the opposite direction to increase pull on the cable, said means comprising a cable, said cable attached to the free end of the lever and a counterweight suspended by said cable.

34. In a car dumper a car holding clamp movable toward the car, a holding cable associated therewith, means associated with one end of the cable for taking up the slack therein as the clamp moves toward the car, means for locking the cable against retrograde movement when the clamp is seated on the car, and means associated with the other end of the cable for increasing the tension therein to draw the clamp toward the car, comprising a lever upon which the holding cable is anchored and positive means for preventing the movement of such anchorage in a direction tending to decrease pull on the cable and means for rotating the lever to move the anchorage in the opposite direction to increase pull on the cable, the lever rotating means including a counterweight.

35. In a car dumper a car holding clamp

movable toward the car, a holding cable associated therewith, means associated with one end of the cable for taking up the slack therein as the clamp moves toward the car, means for locking the cable against retrograde movement when the clamp is seated on the car, and means associated with the other end of the cable for increasing the tension therein to draw the clamp toward the car, comprising a lever upon which the holding cable is anchored and positive means for preventing the movement of such anchorage in a direction tending to decrease pull on the cable and means for rotating the lever to move the anchorage in the opposite direction to increase pull on the cable, the lever rotating means comprising a counterweight, separate supporting means therefor, and a cable interposed between the free end of the lever and the counterweight.

36. In a car dumper a car holding clamp movable toward the car, a holding cable associated therewith, means associated with one end of the cable for taking up the slack therein as the clamp moves toward the car, means for locking the cable against retrograde movement when the clamp is seated on the car, and means associated with the other end of the cable for increasing the tension therein to draw the clamp toward the car, said means including a counterweight.

Signed at Chicago, county of Cook and State of Illinois, this 28th day of November, 1927.
